(57) **CLAIM**

The ornamental design for a table, as shown and described.

DESCRIPTION

FIG. 1 is a perspective view of the top, front and right side of a table showing our new design;

FIG. 2 is a perspective view of the bottom, rear and left side thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof; and,

FIG. 9 is perspective view of the top, rear and left side thereof in an alternate raised position of use.

The broken lines show portions of the table that form no part of the claimed design.
